UNITED STATES PATENT OFFICE.

REINHOLD THOMAS, OF CHICAGO, ILLINOIS.

STOP MECHANISM FOR PHONOGRAFS.

1,298,826.

Specification of Letters Patent.

Patented Apr. 1, 1919.

Original application filed March 15, 1917, Serial No. 154,910. Divided and this application filed June 4, 1917. Serial No. 172,593.

To all whom it may concern:

Be it known that I, REINHOLD THOMAS, a citizen of the United States, residing at Chicago, in the county of Cook and State 5 of Illinois, have invented new and useful Improvements in Stop Mechanism for Phonographs, of which the following is a specification, reference being had to the accompanying drawings, forming a part 10 thereof.

This application is a division of my application No. 154,910, filed March 15, 1917 and now pending.

The purpose of the invention covered by 15 this application is to provide improved means for automatically checking the swinging of the tone arm over the record at a pre-determined point with respect to the playing, as at the conclusion thereof, usually, and automatically stopping the rotation 20 of the record at such pre-determined point in the playing. It consists in the elements and features of construction shown and described, as indicated in the claims.

25 In the drawings:

Figure 1 is a side elevation of a phonograph equipped with this invention, the record carrier being partly broken away and shown in section through the pivot 30 of the brake trip latch on Fig. 2.

Fig. 2 is a plan view of the same, having the sound conduit portion of the record and record carrier broken away for showing the mechanism in detail.

35 Fig. 3 is a detail plan view of the tripping mechanism shown in Fig. 2 with the parts at different position.

Fig. 4 is a section at the line, 4—4, on Fig. 1.

40 Fig. 5 is a perspective view of a locking washer employed in a pivot joint.

In the structure shown in the drawings, A represents the table or top of the cabinet on which the phonograph is mounted. B 45 is the record carrier which may be understood as mounted (by means not shown) for rotation about a vertical axis upon the cabinet top, A, and rotated by a motor (not shown) also supported upon the cabinet top 50 below the same. C represents the record upon the record carrier. D is a block mounted upon the cabinet top, A, having a vertical socket to receive the spindle, 1^a, of a pivot support, 1, on which the unitary structure comprising the sound conduit with the

amplifier as a part thereof, and the sound box, is pivotally mounted for swinging to carry the sound box toward and from the record, said unitary structure including the pivot support being rotatable about the axis 60 of the spindle, 1^a, in the block, D, for carrying the sound box over the record in playing. E is the sound box, E¹, the immediately connecting portion of the sound conduit of which one member, E², extends axially 65 within the outer member or amplifier, E³, carrying at the end remote from the sound box a reflector, E⁴. The detail construction of the sound conduit is not a part of the present invention and no claims therefor are 70 to be made in this divisional application. The drawings show certain features which coöperate in and with respect to the vertical swinging movement of the sound conduit in carrying the sound box toward and from 75 the record, which are in part the subject matter of my said application No. 154,910, being claimed therein, and not claimed or further described in this divisional application. 80

For the purpose of automatically terminating the rotation of the record and stopping the horizontal swinging movement of the sound conduit and sound box over the record at the conclusion of the playing, the 85 following structure is provided:—A trip finger, 7, projecting as a lever arm from a hub or collar, 8, is mounted on the pivot support, 1, so as to be rotatable relatively thereto about the same vertical axis, and is 90 frictionally engaged with said pivot support so as to be rotated therewith as well as to be capable of rotating relatively thereto. Devices for such frictional pivotal mounting comprise the said hub or collar, 95 8, centrally apertured so as to be passed onto and fit upon the spindle, 1^a, and pressed up toward the downwardly-facing shoulder of the head of the pivot support, 1, a fiber washer, 9, being preferably interposed between said hub, 8, and said shoulder of the head; a disk spring, 10, which is centrally apertured and passed onto the spindle, 1^a, up against the under side of the collar, 8; 100 a cup housing, 11, centrally apertured and passed onto the spindle, 1^a, up against the under side of the spring disk, 10, and with its flange inclosing said disk, the washer, 9, and the hub or collar, 8, except that said flange is notched at its upper edge to inter- 105 110

engage said lever arm or trip finger, 7, which extends off from said hub or collar, 8, out through said notch. All the above-mentioned parts are held in place, pressed 5 up toward the shoulder of the head of the pivot support, 1, by means of a locking washer, 12, which has a radial notch, 12^a, leading into its central aperture which is dimensioned for engaging the inner circumference in an annular groove, 1^d, formed in the spindle, 1^a, so that when said washer is passed into place in said groove, as seen in Fig. 4, the said parts are held in place and the spring disk, 10, is compressed to 10 proper tension for producing adequate frictional engagement of the hub or collar, 8, with the pivot support, 1, for the purpose hereinafter explained. The locking washer, 12, is preferably provided on its lower face 15 with a recess, 12^b, around the central aperture, said recess having the unreduced diameter of the spindle, 1^a, of the pivot support, 1, so that the reaction of the spring, 10, locks the locking washer in position on 20 the spindle, 1^a. Upon the upper side of the cabinet top, A, there is mounted a plate, 15, upon which there is pivoted at 16, a trigger, 17, having a finger, 17^a, which extends out past the margin of the record support under 25 the same so as to project in the path of the trip finger, 7, as the latter swings with the pivot support, 1, about the vertical axis of the latter. The trigger, 17, has a locking arm, 17^b, provided with a locking tooth, 17^c, 30 which engages a notch, 18^a, in a flange, 18^b, which projects from the pivot bearing of a brake device, 18, which is pivotally mounted on said plate, 15, and adapted to swing thereabout to engage its brake terminal, 18^c, with 35 a depending flange, B¹, of the record carrier, B. A spring, 20, reacting on the lever arm, 17^b, of the trigger tends to press the tooth, 17^c, against the edge of the flange, 18^b, ready to engage the notch, 18^a, and 40 said notch is positioned relatively to the brake terminal, 18^c, for engagement with said tooth when the brake terminal is pressed against the flange, B¹, for releasing the record carrier. A spring, 21, reacting 45 upon the brake member, 18, operates to swing the brake terminal against the flange to engage the record carrier. The brake member has an operating handle, 21^b, which projects beyond the margin of the record 50 carrier for manipulation of the brake by the operator. The mode of use and operation of the brake and trip device described is as follows: When a record is placed upon the record carrier for playing, the sound 55 box is swung over to a position at which the stylus is at the innermost or final course of the final groove of the record,—that is, at the point at which the playing will be ended, and while it is in this position, the trip finger, 7, is turned about the

spindle, 1^a, of the pivot support, 1, until the end of the finger is in contact with the trigger, 17^a—the brake, of course, being at position for holding the record carrier at rest. The sound box being now swung 70 to carry the stylus to the position for commencing the playing, the brake will be released by swinging the brake handle, 21^b, to the dotted line position, Fig. 2, at which it will be locked by the engagement of the 75 tooth, 17^c, and the notch, 18^a. As the playing proceeds to the end, the trip finger, 7, will be carried into contact with the trigger, 17^a, and the frictional engagement of 80 said trip finger with the pivot support, 1, is sufficient to turn the trigger about its pivot disengaging the tooth, 17^c, from the notch, 18^a, and releasing the brake whose 85 spring, 21, will immediately swing it into engagement with the flange, B¹, of the record carrier, and halt the rotation of the latter.

I claim:—

1. In a phonograph, in combination with the sound-box-carrying member, a pivot support therefor mounted for turning about a vertical axis; a trip finger mounted on said pivot support for turning relatively thereto; means for frictional engagement of said trip finger with said pivot support, adapted to cause them to turn together or relatively to each other; a friction brake for the record carrier; a trigger for locking the brake out of braking position, said trigger having a finger extending in the path of the first mentioned trip finger, and adapted upon encounter thereby to be moved for disengaging the trigger from the brake, and independent springs for actuating the brake and the trigger. 105

2. In combination with a sound-box-carrying member, a pivot support therefor mounted for turning about a vertical axis; a trip finger pivotally mounted on said pivot support for turning thereon about the same axis; a cup-shaped housing rotatably positioned on said pivot support having its flange notched for engaging said trip finger; a spring in said housing reacting between the web thereof and the trip finger, the pivot support having a head provided with a shoulder against which the trip finger is crowded by the spring, and having a groove adjacent to the outer surface of said web of the housing, and a radially-slotted locking washer adapted to be engaged in said groove. 110

3. In combination with a sound-box-carrying member, a pivot support therefor mounted for turning about a vertical axis; a trip finger pivotally mounted on said pivot support for turning thereon about the same axis; a cup-shaped housing rotatably positioned on said pivot support having its flange notched for engaging said trip finger; a spring in said housing reacting between the 115 web thereof and the trip finger, the pivot support having a head provided with a shoulder against which the trip finger is crowded by the spring, and having a groove adjacent to the outer surface of said web of the housing, and a radially-slotted locking washer adapted to be engaged in said groove. 120

web thereof and the trip finger, the pivot support having a head provided with a shoulder against which the trip finger is crowded by the spring and having a groove adjacent to the outer surface of said web of the housing, and a radially-slotted locking washer adapted to be engaged in said groove,

and having its outer face recessed to receive the shoulder of the pivot-support formed by said groove.

In testimony whereof I have hereunto set my hand at Chicago, Illinois, this 23rd day of May, 1917.

REINHOLD THOMAS.
